(57) **CLAIM**

The ornamental design for a plant pot liner, as shown and described.

DESCRIPTION

FIG. 1 a perspective view of a plant pot liner, according to a new design;

FIG. 2 is a front elevational view thereof;

FIG. 3 is a back elevational view thereof;

FIG. 4 is a right side elevational view thereof, with the left side elevational view being a mirror view of the right elevational view;

FIG. 5 is a top plan view thereof; and,

FIG. 6 is a bottom plan view thereof.

The broken lines in the drawings depict portions of the plant pot liner that form no part of the claimed design.

1 Claim, 6 Drawing Sheets
